UNITED STATES PATENT OFFICE

2,143,496

CLOTHES WASHING MACHINE

Thomas G. Poe, Hayti, Mo.

Application August 24, 1937, Serial No. 160,683

3 Claims. (Cl. 68—135)

The present invention relates to an improved clothes washing machine of the portable tub type provided with a suitable stand and rotary agitator means confined within the limits of the tub, and the purpose of the invention is to generally improve upon structures of this general type, the principal novelty being predicated on the agitator construction.

As implied by the preceding opening statement, I am sufficiently conversant with the general state of the prior art to realize that various types of clothes washing machines have been perfected and marketed, some being power operated and others hand operated to actuate the internal water agitating and clothes pounder means. Thus, I aim to provide a structure wherein a new type agitator is incorporated.

More specifically, I have evolved and structurally perfected a revolvable agitator unit such as may be conveniently operated by a hand crank, the same being ingenious in that it is of the dual pounder type, the pounding or impact elements being expressly designed to facilitate circulation of water therethrough while at the same time providing the desired safety clothes washing action.

Other features and advantages will become more readily apparent from the following description and drawings.

In the drawings, wherein like numerals are employed to designate like parts throughout the views:

Figure 1 is a view showing a suitable leg-equipped stand supporting the improved tub-type washer constructed in accordance with my ideas.

Figure 2 is an end view of Figure 1 observing it in a direction from left to right.

Figure 3 is a top plan view with the cover removed to show the interior.

Figure 4 is a longitudinal or central vertical sectional view taken approximately on the plane of the line 4—4 of Figure 3.

Figure 5 is a transverse or vertical section on the line 5—5 of Figure 1.

Figure 6 is a bottom plan view of the novel agitator unit.

Figure 7 is a cross-section, on an enlarged scale, the section being on the line 7—7 of Figure 6.

Referring now to the drawings by distinguishing reference numerals, it will be observed that the tub 8 is supported on an appropriate leg-equipped stand or base 9. The tub, with the removable cover or lid 14 in place, is in the form of

a horizontally disposed cylinder closed at opposite ends. The upper segment is cut away and fashioned into a framing rim 11 having an inwardly projecting ledge 12 to accommodate the marginal supporting flange or lip 13 on the convex cover 14. The cover is provided with an appropriate handle or hand grip 15 to facilitate application and removal. In practice this is a relatively small domestic type washer to accommodate some 15 to 20 gallons of fluid.

The principal objective is to provide in a cylindrical tub of this type an ingenious fool-proof and safety-type agitator unit 16. This is a metal structure and is characterized by a pair of segmental end or head plates 17 having their apex 15 ends connected with appropriate journals 18. The journals are mounted for rotation in suitable bearings 19 having stuffing boxes. One journal projects and carries a hand crank 20 to facilitate rotation of the agitator unit 16 through a complete revolution. It is obvious, of course, that power operated means can be employed instead of a hand crank. Swung or supported horizontally between the head plates 17 are spaced parallel clothes pounders 21 forming water agitating baffles. These are duplicate in construction and each is of triangular cross-sectional form as seen in Figure 7. The bottom plate 22 is provided with transverse longitudinally spaced slots 23 as brought out to advantage in Figure 6. The inwardly diverging walls denoted by the numerals 24, 25 are imperforate. The companion outwardly slanting or diverging walls 25 are provided with a plurality of orifices or apertures 25^a to set up the desired agitation and circulation of water such as is contained in the tub. The triangular pounders are fashioned from metal and provided with attaching end members 26 suitably attached to the bifurcated ends of the end plates 17. Thus, the gist of the invention resides in the provision of the spaced parallel, or substantially so, agitating members 21, these being triangular in cross-sectional form and having suitably arranged apertures to facilitate liquid circulation. This particular shaping and arrangement seems aptly fitted for the purposes intended and, from experience, is shown to be well adapted to the usage intended.

As before indicated, I am sufficiently well acquainted with the general state of the prior art to realize that tubs with movable agitator means therein are old in many styles and varieties. In the small washer constructions, however, it has been generally considered proper to use oscillatory pounders and agitators. These are fre-

- quently of the single bar or element type. Thus, the essential newness here is predicated upon a revolvable agitator wherein the baffle or pounder members revolve through a complete orbital path.
- 5 Not only this, the pounders themselves are of such shape and arrangement as to avoid tearing of the contents of the tub and to at the same time insure safe and easy removal of dirt. I shall not, however, attempt to go into the commercial or scientific phases of the invention, for, persons skilled in the art to which the structure relates are well posted on these phases.
- 10 It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

1. A clothes washing machine of the class described comprising a relatively fixed tub, said tub being of cylindrical cross-sectional form, and an agitator mounted for rotation in said tub, said agitator embodying segmental end plates, and pounder members supported between the outer peripheral edge portions of said plates, said pounder members being spaced apart and each

member being of substantially triangular shape in cross section, with one wall located adjacent the inner circumference of the tub, and said wall having transverse slots therein, another wall having openings therein and the third wall being imperforate, and each pounder member being of hollow construction.

2. As a component part of a washing machine of the class described, an agitator unit comprising an elongated pounding element of triangular shape in cross-sectional form and hollow, the outer wall of the element being formed with longitudinally spaced transversely disposed slots and one of the other walls being provided with a multiplicity of orifices.

3. As a component part of a clothes washing machine of the class described, an agitator unit comprising a pair of end plates adapted for rotatable mounting in a clothes and water containing tub, and a pair of duplicate agitating and pounding members supported between said plates, said pounding members being spaced apart and having their ends connected with the plates and each member being of triangular shape in cross section and of hollow construction, that wall of each member adjacent the tub having transverse slots therein, that wall which faces the other pounding member being imperforate, and the third wall having perforations therein.
